SAFETY HANGER PIN GUARD

Gilbert Charles McMasters, Frankfort, Ind.

Application October 17, 1935, Serial No. 45,496

10 Claims. (Cl. 188—205)

This invention relates to a novel and improved guard in the form of an attachment for standardized keeper means used on certain wheel equipped trucks such as are provided on present day railway cars.

In order that the invention may be better understood, it is to be pointed out by way of introduction that the improved guard or accessory is in the form of a sectional pin retention clip expressly designed to be used on "Bettendorf", "Vulcan" and other series of trucks that have pin hole brackets. It is a matter of common knowledge that these types of trucks are provided with removable brake hanger rods or pins and these are inserted endwise thru special adapter openings formed in the sides of the frame structure of the truck. As the brake, hangers and brake beams have to be renewed and repaired from time to time it is necessary to remove and replace said brake hanger rod or pin. On the types of trucks indicated the frame is provided outwardly of the adapter hole with integral keeper means. The most common type comprises a pair of superimposed parallel hook-like extensions which register with the adapter holes.

At the present time it is the common practice to employ a pin retention or guard device which is substantially L shaped in form. In other words it is in the nature of an L-shaped iron strap, the shank portion being inserted through the keeper hooks. The extending end of the shank portion is then adapted to be heated with an acetylene torch, after which it is bent at right angles around the adjacent ends of the keeper hooks. The result is that the strap arm then becomes a sort of a U-shaped clip and spans or closes the space between the hooks and also functions as a temporary closure for the adjacent adapter hole and this prevents accidental displacement of the brake hanger rod or pin. To remove this pin retention or guard it is necessary to heat it on one end and hammer it back. Manifestly however there is considerable expense and unnecessary time utilized by following this method and for this reason I have devoted considerable time and thought to the development of an improved guard which is susceptible of being used either with the closed or open hook type keeper on the car truck.

Generically the preferred embodiment of the invention comprises a pair of substantially duplicate companion sections or units designed to cooperate in a complementary manner to provide a safe and dependable pin guard clip.

My aim is to generally improve upon devices susceptible of being classified in this particular

line of endeavor by providing one which is, comparatively speaking, economical, susceptible of expeditious application and removal, safe and reliable, and otherwise aptly fitted to fulfill the requirement of the trade and industry.

Other features and advantages will become more readily apparent from the following description and drawings.

In the drawings:

Figure 1 is a side elevational view showing a conventional car body truck and showing the improved safety clip fully in place at the left, and partly in place at the right.

Figure 2 is a perspective drawing showing the duplicate pair of companion sections which go to 15 make up the improved unitary safety clip.

Figure 3 is a view showing the sections coupled or fastened together by a cotter key such as is employed in carrying the idea into practice.

Figure 4 is an enlarged vertical sectional view 20 showing the aforementioned brake rod or pin, the frame and keeper hooks and the safety clip associated with said hooks.

Figure 5 is a horizontal sectional view of the assemblage disclosed in Figure 4.

Figure 6 is a perspective view similar to Figure 3 showing, instead of the resilient metal type clip, a pre-cast relatively sturdy type of the rigid variety which may be used under certain circumstances.

Figure 7 is a view similar to Figure 5 showing the clip of Figure 6 as it is used.

In the drawings in Figure 1, the conventional "Bettendorf" car truck is shown and indicated by the numeral 8. The only features of this with which I am especially concerned here are those shown better in Figures 4 and 5. Referring to these figures it will be observed that the brake hanger rod or pin is denoted by the numeral 9 and one end of this is removably fitted in an adapter hole in the frame of the truck. Outwardly of this and cast integral with the frame of the truck are the so-called keeper hooks 10 and 11. These are disposed in superposed parallelism for cooperation with the adapter hole 40 and allow the pin 9 to be inserted and removed as desired.

I call attention at this time to Figure 2 which shows the preferred embodiment of the invention, that is a resilient or spring metal type of clip. 50 The clip is of two-part construction and the parts or sections may be conveniently designated substantially U-shaped units 12 and 13. They are identical in construction and fashioned from resilient cheap metal. This makes it possible to 55

manufacture the parts at low cost. The inner arms 14 and 15 are adapted to overlap when forced together as shown in Figure 3. The outer arms 16 have their free end portions bent laterally outward as indicated at 17 to form abutting and fastening flanges. These flanges are apertured to accommodate a cotter key 18 which is inserted with its prongs bent around the flanges as shown in Figure 3. The two clips are assembled around the hooks 10 and 11 as shown better in Figures 4 and 5. In other words one clip is inserted at one side and then the other clip is inserted to bring the ends 14 and 15 into overlapping binding resilient gripping relation on the bill portions of the keeper hooks 10 and 11. The flanges 17 are also thus matched and hence the parts are carefully proportioned to accomplish this result. Then the cotter key is inserted and its prongs are bent and are virtually locked in place. Its primary purpose is to take the place of the aforementioned L shaped strap arm which is ordinarily employed at the present time on railroads. It is my idea that these two parts are far superior to the old style safety strap iron. To those familiar with articles of manufacture of this general classification it is evident that the clip, as a unit, is quite inexpensive not only to the manufacturer but to the user. The parts can be made satisfactorily on an air press which will bend them and punch the cotter keyholes all in one operation and this adds to the efficiency and utility of the article as a whole. As before indicated the device in addition to serving satisfactorily as a safety guard will save much time and minimize expense so far as the railroad company is concerned. The parts can be turned out in production lots and will serve satisfactorily even when made from a cheap grade of light weight metal. No particular skill is required in applying or removing the clip and it is unquestionably safe and reliable in its operation. To my mind it is a needed improvement over the present retention means and method of applying it in place and is consequently well fitted for its special purposes.

In the modification shown in Figures 6 and 7 the same fundamental idea is carried into effect. Here the companion or complementary sections 19 and 20 are rigidly cast in pairs so that the connecting and fastening flanges 21 may come together in cooperating relationship to receive the cotter key so that the connecting end portions 22 and 23 will come together neatly in overlapped relationship. The parts 22 and 23 are of corresponding length and thus designed to promote easier assembling in that they are not likely to become distorted or corroded and this form of the invention therefore has certain advantages over the spring type. Taking everything into consideration however it is thought that the spring type clip will serve adequately well in that it is attended with certain appreciable commercial aspects and advantages.

The principal idea, generically speaking, is to provide the flanged sections of general U-shaped form which can be alternately slipped over the supporting or retention hooks of the existing keeper means on the car truck, the overlapping portions serving to bridge the space between the hooks so as to effect the principal guard means, and the flanges being readily accessible so as to accommodate the cotter key or other fastening means.

Structurally speaking, and by way of introduction to the claims, it is to be pointed out that

each part or section is in the nature of a U shaped unit and includes a connective or bight portion and a pair of spaced parallel end portions. It is to be noted that one end portion, that is, the part which goes into the keeper, is longer than the other end portion. Then, too, the last named end portion which is on the exterior of the keeper has its free end bent laterally outward and apertured to provide an abutment as well as a retention flange to accommodate the cotter key.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice, if desired.

Having thus described the invention, what is claimed as new is:

1. In a structural assemblage of the class described, in combination, a car truck frame provided with an adapter hole for accommodation of the adjacent end of a brake hanger rod, and further provided adjacent said hole with rod retention guard holding means, and guard means associated with said holding means and comprising a pair of quick separable and attachable units. 25

2. As a new article of manufacture, a safety guard clip of the type described comprising a pair of quick connectible and separable units detachably applicable to operative position on a car truck frame and including cooperable portions to serve as an effective closure and to guard against endwise displacement of a complemental hanger rod. 35

3. As a new product of manufacture, a safety guard clip of the type described comprising a pair of U-shaped duplicate sections adapted to be assembled in abutting relationship, corresponding end portions thereof being disposable in overlapping relationship and the remaining corresponding ends being provided with outstanding abutting flanges apertured to accommodate releasable fastening means. 40

4. As a new article of manufacture, a pair of duplicate U-shaped spring clips, the inner corresponding end portions thereof being adapted to come together in overlapping relationship, the free end portion of the opposite ends thereof being bent laterally outward and apertured to provide assemblng and retention flanges, and a cotter key for cooperation with said flanges to facilitate assembling and maintenance. 50

5. As a new product of manufacture, a safety guard attachment for keeper means on a car truck of the class described comprising a pair of rigid precast U-shaped units, corresponding end portions thereof being disposed together in overlapping relationship, the free end portions of the remaining ends thereof being bent laterally outward to form rigid abutting flanges and said flanges being apertured to accommodate a cotter key or the like. 60

6. As a component part of the structure of the class described, a U-shaped unit including a connective or bight portion and a pair of end portions, one end portion being longer than the other and the last named end portion having its free end bent laterally outward and apertured to provide a retention flange. 70

7. In a structural assemblage of the glass described, in combination, a car truck frame provided with an adapter hole for accommodation of the adjacent end of a brake hanger pin, removable sectional guard and pin retention means adapted to cover the hole and to prevent endwise accidental displacement of said pin through the hole, and fixedly connected supporting hooks on said frame to maintain said guard means satisfactorily in operating position.
8. In a structural assemblage of the class described, in combination, a car truck frame provided with an adapter hole, a brake hanger rod having one end portion disposed in said hole, keeper means on the frame in alignment with said hole, and guard means detachably cooperable with the keeper means, said guard means including a closure plate for the hole, and readily accessible flanged retention means for the plate.
9. As a component part of a structural attach-

ment of the class described, a closure unit for the adapter hole of a brake hanger rod embodying a plate adapted to extend across and cover the hole, said plate being fashioned to cooperate with the keeper means within the vicinity of the hole and being provided with flanged retaining means cooperable with said keeper means, said retaining means being in parallelism to the plate.

10. As a new article of manufacture and as a component part of an attachment of the class described, a safety hanger pin guard comprising a cover plate for the adapter hole in a frame in which the hanger rod or pin is disposed, said plate being constructed to cooperate with retaining hook on the frame adjacent to and in alignment with the hole, and said plate being of preformed type and including laterally bent connecting means at one end adapted to maintain the plate in operative position.

20
